UNITED STATES PATENT OFFICE.

HEINRICH FETZER, OF PFORZHEIM, GERMANY.

EARRING WITH CLAMPING BOW.

Application filed February 2, 1927, Serial No. 165,388, and in Germany May 1, 1926.

This invention relates to an ear-ring with clamping bow which differs from ear-rings of this type and of known construction by the shape and manner of fixing of the clamping plates.

According to the invention the clamping plates, which are arranged on the free ends of the two elements of the bow held together by spring action and adapted to be opened, are of the shape of small cups engaging the one over the other, the cup on the hinged bow element being mounted on its element so that it can be oscillated in any direction and so that it adjusts itself at the closing of the clamping bow uniformly onto the skin of the lobe of the ear. For perforated ear lobes the rivet, by means of which the loose clamping plate is mounted on the corresponding bow-element, is extended to form a pin.

This arrangement presents the advantage that the ear-ring is oscillatably attached to the ear lobe which is pressed into the cavity of the one clamping plate. A further advantage is that no irritation of the skin is produced as the rim of the clamping plate presses the ear lobe with uniform pressure at all points.

An improved ear-ring is shown in the accompanying drawing, by way of example, in which

Fig. 1 shows in side elevation, partly in section, an ear ring with closed clamping bow, the hinged clamping element with the oscillatable clamping plate being indicated in the open position by dash-dot lines.

Figs. 2 and 3 show each one clamping plate on the end of the corresponding bow element in elevation.

Fig. 4 shows in section the clamping plate with a pin for the ear hole.

The clamping bow for the ear-ring consists of the stationary element *a* to which a pendant *i* is suspended which carries a precious stone or is ornamented with precious stones, and of a hinged element *b*. The element *b* is hingedly fixed to the element *a* by means

of a hinge *c*. The hinged element *b* is secured in the open or closed position by the action of a blade spring *d* which bears onto the one or other of the edges *e* of the hinge *c* said edges standing at right angles the one to the other.

On the free end of each bow element *a* and *b* a clamping plate *f*, *g* respectively is arranged, said clamping plates being cup-shaped and designed to hold between them the lobe of the ear, the cup-shaped clamping plate *f* on the stationary bow element *a* pressing the ear lobe into the cavity of the clamping plate *g*.

The clamping plate *f* is soldered upon the free end of the stationary bow element *a* and serves as mounting for a pearl *h*, a precious stone, or the like. The clamping plate *g* is fixed by a rivet on the free end of the movable element of the clamping bow so that it can oscillate in all directions and adapt itself in the closing position perfectly to the ear lobe. This clamping plate *g* presses on the ear lobe at uniform pressure at all points so that irritation of the skin is avoided which might be caused if a portion of the edge of said clamping plate should press more strongly onto the ear lobe than the remainder of the edge.

For pierced ear lobes the rivet of the clamping plate *g* is extended to form a pin *k* designed to penetrate into the ear-hole.

I claim:—

A clamping earring, comprising in combination, a clamping bow composed of a stationary element and of a movable element, a spring-controlled hinge connecting said movable bow element to the said stationary bow element, a clamping plate rigidly fixed on the free end of said stationary bow element, a rivet in the free end of said movable bow element, and a cup-shaped clamping plate loosely mounted on said rivet.

In testimony whereof I affix my signature.

HEINRICH FETZER.
